John R. Patrick, Baltimore, Maryland
Setters Patent

The Schedule referred to in this Letters Patent and making part of the same containing a description of the words of the said John R. Patrick himself of his improvement in the application of Valves to Steam Engines, which he denominates the Self-Balancing slide valve & shifting cam.

Whereas I, John R. Patrick of Baltimore in the State of Maryland have invented a new and useful improved slide valve for Steam Engines, with an improved cam suitable to the same, which I denominate the self-balancing slide valve and shifting cam. Now Be it known that in conformity with the requirements of the Law granting patents for useful inventions. I do hereby declare that the following is a full and exact description of my said improved valve and cam invention being had to the drawing which accompanies and makes a part of this Specification.

I denominate the Valve self Balancing because it is regulated that by the action of the steam itself the pressure of the valve upon the valve seat is always the same however much the elastic force of the steam may vary in the Boiler and other parts of the Engine.

The Cam I denominate shifting, because by shifting a circular plate attached to it backward or forward, the steam is cut off earlier or later in the stroke, which is often required by changes of ^{motion} fuel or resistance of the Engine. In some respects this valve and cam (but more particularly the latter) are similar to others, now in use, and to such parts which are so. I of course make no claim, but besides the self-balancing apparatus to be presently described there are some points in the arrangement of the steam ways in the valve and valve seat, which are new and which I consider as improvements, these are the exhaust passages in the valve and valve seat. No 1. in the accompanying drawing represents a valve seat placed upon an ordinary side pipe of an Engine & shows in what it takes the proper proportion for an eccentric motion.

No 2. represents the face of a valve adapted to No 1. No 3. is a section through the middle of the valve in a transverse direction and vertical to its face. No 4. is a cross-section longitudinally. No 5. shows a similar section of the valve its seat and a portion of the side pipe. No 6. is a perspective view of the whole self-balancing valve and its appendages excepting the cam. No 7. is a modification of the valve and seat, to shut off at any part of the stroke which may be determined upon. No 8. is a shifting cam suitable for No 7. the shifting projection plate being set at half stroke. No 9.

the opening a is for the admission of steam into the cylinder through the steam pipe b.
The two parallel openings c c are for the alternate admission and escape of the steam
to and from the two ends of the cylinder being conducted into them through the cavity in the
valve e and from them by the passages in the valve c c to the longitudinal passage d
thence to the longitudinal passage in the seat h. thence out through the escape e, the cor-
responding openings in the valve and seat are designated by the same letters.

The openings a c c of the seat are all the same dimensions, and the opening d is of the
same width with them, and equal to the width of the valve, and the spaces between
them. In the valve b is the centre opening or cavity a which may be denominated the
Steam Chest must be sufficiently wide to embrace the centre opening a and one of the
end openings c c of the seat. In sliding therefore by means of a cam or eccentric motion
the steam will be alternately admitted into and discharged from each end of the cylinder
b through the different openings of the valve and seat. For shutting off at half stroke
or any other desired point the construction of the valve is the same as that already described
but there is a difference in the proportions of the openings and spaces in No 7. The
middle opening of the seat is of double the width of the end ones c c, the spaces between
them are of the same width with the middle opening and the cavity a of the valve or
steam chest extends from the centre of the middle opening to the extreme edge of a shelf
of the end openings, or the centre opening of the seat may be rather less than twice
the width of one of the end openings and the spaces rather less than that. The propor-
tions of the valve will of course vary with those of the seat, every competent Engi-
neer will readily perceive the effect of this arrangement and how it may be varied
and adapted to shut off at any desired part of the stroke by moving back wards or
or forwards the circular plate g of the shifting cam No. 8. The dotted lines show
the form of the cam when the plate is shifted so to g. In No 6. b is the steam pipe
and q is a cylinder or chamber for containing a piston or plunger, into the lower
end of which cylinder steam is admitted through the tube b. The piston rod c extends
up to and is connected with the lever f which has a knifedge or circular ful-
crum under the crosspiece h of the frame. The stem m has a cavity in
the upper end to receive the lever and there is a similar cavity n in the valve to receive
the lower end of the stem. This mode of forming joints, although not essential to the
general plan is extremely convenient as it affords ample bearings all of which may
be made to move in oil, it also allows the valve to be taken away without the treat-
ment le

afterwards a stone and replaced in the same manner. The size of the plunger or piston in a must be such as shall produce the self-balancing effect operating by means of the lever upon the valve. In making this calculation the area of one of the end openings of the seat added to the area of the steam chest or cavity of the valve is the area of the plunger or piston with a lever of equal length at both ends, but the end of the lever must the plunger will be longer than that next to the valve so necessarily will the area of the plunger be less than the area of the steam chest and one of the end openings. The nut p upon the piston rod acts upon the spiral spring q which has its lower bearing upon the bow r and by means of this the degree of friction may be regulated. On the inside of the spiral spring q is a cylinder with a flange t directly below the nut p. This cylinder is to protect the screw on the upper part of the piston Rod i. The lower end of the cylinder passes through the upper part of the bow r. The lower end of the piston Rod terminates at the bottom of hollow of the plunger. w which should be about the centre of the staffing ^{top} the vibration is thus taken from the Plunger while the other parts connected with the lever conform fully to its action. (What I claim as my invention is the general form of the valve & its appearance as herein described by means of which the self-balancing principle is applied the elastic force of the steam acting upon a piston being thereby made to react upon the the valve with any desired degree of force. Also the application of a shifting projection to the cam (for the purpose already described) which combines in a single cam the means of shutting off at any part of the stroke with the principal motion of the valve.) And I do hereby declare that I do not intend to confine myself to the precise arrangement herein shown but to vary the same in any manner which I may deem proper as a substitute for the throttle valve and for the purpose of balancing all valves now in use, using vacu-um with pressure when necessary to effect that purpose. While the same principle is applied and a similar effect produced.
